UNITED STATES PATENT OFFICE

107,403

DESIGN FOR A SOUP CUP OR SIMILAR ARTICLE

Karl Bayreuther, Selb, Germany, assignor to The Rosenthal China Corporation, New York, N. Y., a corporation of New York

Application August 1, 1936, Serial No. 64,170

Term of patent 14 years

To all whom it may concern:

Be it known that I, Karl Bayreuther, a citizen of Germany, residing at Selb, Bavaria, Germany, have invented a new, original, and ornamental Design for a Soup Cup or Similar Article, of which the following is a specification, reference being had to the accompanying drawing, forming a part thereof.

Fig. 1 is a perspective view of the soup cup or similar article showing my design.

Fig. 2 is a side elevational view of the same.

Fig. 3 is a sectional view of the body portion thereof taken along the line 2—2 of Fig. 2.

The body of the cup which embodies my new design has a comparatively shallow or squat shape

which gradually slopes upwardly on the sides to the top peripheral edge. The contour of this top edge provides an overhanging ledge on the upper surface of which is an inwardly-inclined flat, narrow but very definite plane surface. The oppositely projecting handles partake of the same flat appearance and accentuate the shallow character of the entire design. The cup is mounted on a flanged base having an outer definite peripheral bead.

I claim:

The ornamental design for a soup cup or similar article as shown and described.

KARL BAYREUTHER.
